UNITED STATES PATENT OFFICE

91,586

DESIGN FOR A CHEWING GUM CARTON

John McCollum, New York, N. Y.

Application December 18, 1933. Serial No. 50,106

Term of patent 14 years

To all whom it may concern:

Be it known that I, JOHN McCOLLUM, a citizen of the United States, residing at the Borough of Manhattan, in the city, county, and State of New York, have invented a new, original, and ornamental Design for a Chewing Gum Carton, of which the following is a specification, reference being had to the accompanying drawing, forming part thereof.

Fig. 1 is a top plan view of a chewing gum carton showing my new design.

Fig. 2 is a front elevation of the same, the

numerals 5 and 6 designating openings in the front face of the carton through which are visible the edges of the flat sticks of chewing gum or the wrappers for said sticks, which are intended to be inserted into the carton.

Fig. 3 is a side elevation of either side of the same, both sides being identical.

Fig. 4 is a rear elevation of the same.

I claim:

The ornamental design for a chewing gum carton as shown and described.

JOHN McCOLLUM.
